UNITED STATES PATENT OFFICE.

WILLIAM D. WRIGHT, OF PROVIDENCE, RHODE ISLAND, ASSIGNOR TO UNITED ELECTRIC RAILWAYS COMPANY, OF PROVIDENCE, RHODE ISLAND.

RAILWAY-TRANSFER CLAMP.

Application filed July 20, 1925. Serial No. 44,859.

The present invention consists of a railway transfer clamp and embodies a combination clamp for embracing the transfer packet and cutter for severing the transfers.

5 Objects of the invention are to provide a clamping member which embraces the transfers and is slideable thereon to position the clamp at any predetermined point on the transfers at which point it is desired to sever one or more of the latter; to provide a 10 clamp of this character which yieldingly engages the transfers to prevent casual displacement of the clamp; to provide a clamp the length of which is in excess of the width 15 of the transfers so that the clamp may be disposed transversely across the transfers or at an angle oblique to the longitudinal axis of the latter to permit diagonal severance of the transfers; and to provide a 20 clamp of very simple and durable construction capable of expeditious engagement on and disengagement from the transfers.

Other objects of the invention will be apparent from the following description of the 25 present preferred form of the invention taken in connection with the accompanying drawings wherein:—

Fig. 1 is a side elevational view of a clamp constructed in accordance with this invention a part thereof being broken away to 30 disclose details;

Fig. 2 is a top plan view of the clamp illustrating the application of the same on a 35 packet of street railway transfers;

Fig. 3 is a horizontal sectional view of the clamp looking at the spring in top plan view;

Fig. 4 is a bottom plan view of the clamp; and

Fig. 5 is a detail fragmentary transverse sectional view of the clamp illustrating its application on a packet of transfers.

In order to illustrate the application of the present invention a packet of street railway transfers 6 is shown which may be of standard or especial construction or compilation, and, in the present instance, is shown to be lined transversely to provide a series of compartments 7 in which indicia 8, representative of the hours and fractions thereof, is printed.

The clamp constructed in accordance with this invention is especially adapted for use on different species of transfer which is sev-

erable either transversely or diagonally to 55 indicate the specific hour and fraction of the hour that the transfer is issued.

The present clamp consists of a base plate 9 which may be of substantially oblong configuration as shown and is equipped with a yoke 10. The yoke in the present instance consists of a metallic rod the ends of which are bent at right angles to provide a U-shape structure the terminals of which penetrate the base plate 9 near the ends of the latter and are swaged to fixedly secure the yoke member and base together. Mounted between the base plate 9 and the vertex of the yoke 10 is a floating follower plate or bar 11 the ends of which are provided with 60 openings 12 which complement and slidably receive the ends of the yoke 10. The follower plate 11 is normally urged into engagement with the vertex of the yoke 10 by 65 a semi-elliptical spring 13 the ends of which 70 latter are provided with substantially U-shape notches 14 in which the ends of the yoke member are positioned.

In use of this device, the follower bar 11 is urged toward the base plate 9 against the 75 resistance of the spring 13 to permit introduction of the transfer packet between the follower plate and the vertex of the yoke. After this has been done the follower plate is released and permitted to yieldingly impinge against the bottom of the transfer packet due to the inherent resiliency of the 80 spring 13. The vertex of the yoke impinges against the top of the transfer packet. By 85 preference, the lateral margins at the inner 90 face of the vertex of the yoke are beveled to provide cutting edges 15 to facilitate severance of one or more of the transfers in an apparent manner. It will be noted, especially upon reference to Fig. 1 of the drawings, that the terminals of the spring 13 are in intimate contact with the ends of the follower plate 11, even beyond the ends of the 95 yoke 10, so as to simultaneously elevate both ends of said plate and eliminate the 100 possibility of either end thereof binding. Since the clamp is of the same configuration on both sides it is apparent that it may be reversed without in any way changing its 105 manner of use. The parts of the clamp are practically indestructible, with the possible exception of the spring 13, the cost of which latter is almost negligible and may be quick-

ly replaced in an apparent manner. It is, of course, to be understood that although this clamp is preferably made of metal, I am aware that it may be constructed of other materials and used in the same manner without departing from the spirit and scope of the present invention. Moreover, changes may be made in the details of construction, proportion and arrangements of parts within the scope of the claim hereto appended.

What is claimed is:—

A street railway transfer clamp including a base plate equipped with a U shaped yoke the ends of which are fixed in said plate and the closed end of the yoke provided with cutting edges, and a follower plate yieldingly mounted between said base plate and the closed end of the yoke to urge the transfers against the latter. 15

In testimony whereof I affix my signature.

WILLIAM D. WRIGHT.
